UNITED STATES PATENT OFFICE

LOUIS A. KOCH, JR., OF LOUISVILLE, KENTUCKY

ELECTRIC SIGN

Application filed June 8, 1931. Serial No. 542,999.

My invention relates to electric signs and particularly to those in which the sign element is either directly produced by a "neon" tube or an independent sign element is employed and the desired illumination thereof secured through the instrumentality of a "neon" tube. My sign is particularly adapted for association with motor vehicles and when so associated the illumination of the "neon" tube is effected through connection with the electrical system of the vehicle, the tube or tubes, as the case may be, being included in the secondary or high tension circuit of such system.

It is the purpose of my invention to provide a sign of the type specified embodying a casing with a "neon" tube or tubes therein, together with a novel construction for mounting the tubes and electrically connecting them without the casing to a source of current, the aforesaid mounting construction being designed to avoid breakage or displacement of the tube or tubes, under the influence of vibration, while the aforesaid electrical connections are of such flexibility as to readily respond to vibrations without derangement thereof and without imposing any breaking strain upon the tube.

A further purpose of my invention is to provide a sign casing which is divided into front and rear compartments by a transverse partition with a "neon" tube mounted in each compartment. Such casing being adapted for mounting upon the top of a vehicle, so as to provide distinct illuminated signs visible respectively from the front and rear. This construction of casing is also particularly adapted for use in connection with taxicabs wherein it is mounted so that the rear sign in the casing will be constantly visible to passengers within the passenger compartment of the cab. When used in the latter connection the illumination of the sign visible from the front may be so constructed that when illuminated it will indicate that the cab is vacant, such illumination being under the control of the driver through the instrumentality of a readily accessible switch.

With the foregoing and other purposes in view my invention consists in the details of

construction and in the arrangement and combination of parts to be hereinafter more fully set forth.

In the drawings chosen to illustrate my invention the scope whereof is set forth in the appended claims,

Figure 1 is a perspective view of a taxicab showing my invention associated with the ignition system thereof;

Figure 2, a front view of the sign casing with the front or sign element removed and disclosing the illuminating "neon" tube and its mounting;

Figure 3, a section on the line 3—3 of Fig. 2;

Figure 4, a section on the line 4—4 of Fig. 2;

Figure 5, a rear view of the case showing the "neon" tube employed in the rear compartment together with its mounting and connections;

Figure 6, a front view of a cylindrical identifying lamp embodying my invention, such lamps being commonly used on taxicabs to indicate the type of vehicle as it approaches;

Figure 7, a section on the line 7—7 of Figure 6; and

Figure 8, a diagrammatic view showing the wiring connections between the vehicle battery, vibrator coil and signs.

Referring to the drawings A indicates a taxicab, whose ignition system embodies a battery B, and vibrator coil C, which latter is enclosed in a metallic case grounded with the vehicle for a purpose that will presently appear. This metallic case is clearly shown in Figure 8 at 10 and embodies lateral wings 11 provided with recesses 12 which receive respectively studs 13 whereby the case and the vibrator coil may be easily applied or removed, such construction permitting quick and economical substitution service.

The sign element of my invention is shown as comprising a casing D having a transverse partition 14 which divides the interior of the casing into a front compartment 15 and a rear compartment 16. Projecting from the partition 14 into the front compartment are studs 17, the free ends of which are dished

to form seats or sockets 18 for a "neon" tube 19, which in this instance is shown straight. In order to hold the tube 19 to the studs 17 I lace through the latter a wire 20 and then train the wire about the tube; finally twisting the ends thereof together as at 21. The outer end of the front compartment 15 is adapted to be closed by a sign element. In this instance I show the sign element as comprising 10 transparent glass panes 22, the inner of which bears against rubber bushings 23 carried by and projecting from the partition 14. Between the panes I insert a suitable stencil 24 formed to delineate the desired sign when 15 the tube 19 is illuminated. A retaining frame 22' holds the panes 22 and stencil 24 in place and permits the ready removal thereof for the insertion of a different stencil when desired. Mounted on one side of the case D 20 within the compartment 15 is an insulating block 25 which carries a binding screw 26 to which latter one end of the tube 19 is connected by an easily flexed conductor 27, while its other end is connected to the metallic case 25 by a similar conductor 28 through the instrumentality of a binding screw 29 mounted in the adjacent end wall of the casing.

Disposed in the rear compartment 16 is a "neon" tube 30 shaped to provide a different 30 sign from that delineated by the stencil 24. This tube is held in upright position as shown in Figure 5 by studs 31 carried by the partition 14, the free ends of which studs are dished to receive the tube. A wire 32 is 35 laced through each stud and bound around the tube to hold the latter in the dished end of the stud. The tube 30 rests at its bottom on cushions 33 formed of rubber or any suitable material which is adapted to absorb vibration, said cushions being immovably secured to the bottom of the compartment 16 by cement or in any other suitable manner. Disposed within and secured to one side of the compartment 16 is a post 34 of insulating 40 material and on which is mounted a binding screw 35. Attached to this binding screw is one end of a flexible conductor 36, the other of which is secured to the adjacent end of the tube 30. Secured to the other side of the 45 compartment 16 is a post of insulating material 37 similar to the post 34 and having mounted thereon a binding screw 38. A flexible conductor 39 connects the adjacent end of tube 30 and screw 38, while a conductor length 40 extends through the partition 14 and connects the screw 26 in compartment 15 with the screw 38 in compartment 16.

In Figures 5 and 6 I have shown my invention applied to an identifying lamp for 60 use on taxicabs, such lamp being indicated generally at E and embodies a substantially cylindrical casing 41 having a lens facing 42 at its forward end. A bracket 43 supports the lamp from the body of the cab. Within 65 the casing 41 I mount radially disposed tube

supporting studs 44 which are dished at their free ends to form a socket or seat receiving the "neon" tube 45, the latter being bent to form substantially concentric circles conforming to the cylindrical shape of the casing, although it will be understood that formation or shaping of the tube 45 can be altered to meet the requirements of any shape of casing. The ends of the tube 45 terminate in parallel straight portions 46 and 47 extending transversely of the casing 41. A post 48 of insulating material is mounted within the casing 41 and carries a binding screw 49 electrically connected to the end 46 of the tube 45 by a flexible conductor 50, while the other end 47 of the tube is grounded to the casing 41 by a flexible conductor 51. The tube 45 is held to its seat on the studs 44 by binding wires 52 which are laced through respective studs and then secured about the tube by twisting their ends together. Vibration of the tube 45 is absorbed by a cushion 53 mounted in the bottom of the casing and upon which the tube rests. A conductor 54 leading from the secondary or high tension terminal 55 of the coil C is carried into the casing 41 and connected with the screw 49.

In Figure 8 I have illustrated diagrammatically the lamp E and the sign elements within the casing D in association with the coil C and battery B. By reference to this figure it will be apparent that a conductor 56 leads from the secondary terminal 55 of the coil C into the compartment 16 where it is connected with the screw 35. A conductor 57 leads from the battery B to the primary terminal 58 of the coil C, while the opposite side of the battery is grounded to the stud 13 by a conductor 59 which latter has interposed therein the usual interrupter or timer 60. It will of course be understood, as previously noted, that the metallic coil casing 10 is grounded as indicated at 61 and that the connections of the coil with the case 10, which are not visible, are such as to properly conform to the wiring shown. The tube 45 of lamp E is grounded through casing 41, conductor 62 and coil case 10. In order to provide for disconnecting the tube 19 to extinguish the illumination of the "vacant" sign element 24 I lead from the screw 26 to the exterior of the casing a conductor 63 which is grounded at 64. Included in this conductor is a switch 65 adapted in its open position to cause the current to traverse the tube 19 and ground through conductor 66 and casing 10. When the switch 65 is closed the current is shunted to ground by way of conductor 63 and the tube 19 cut out. The illuminated sign provided by the structure shown in Figures 2 to 5 is adapted to be secured to a taxicab in the manner illustrated in Figure 1; brackets 67 being provided on the casing D for security to the body of the cab. In this arrangement the compartment 130

16 is closed by the windshield of the cab. Should it be desired to use the sign on top of a vehicle, the compartment 16 can be closed by the application of a clear pane of glass. 5 In the latter disposition both compartments of the sign could be utilized directly for advertising purposes with each presenting a distinct subject matter. A stop clamp 68 is mounted on the conductor 63 within compartment 15 to prevent strain on the post 25 if 10 a pull should be accidentally exerted upon said conductor.

I claim:

1. In an electric sign, a casing, a transverse partition in the casing dividing the latter into front and rear compartments, a "neon" tube in one compartment bent to provide a sign, a "neon" tube in the other compartment, a changeable sign producing 20 stencil device closing the latter compartment visualized by the "neon" tube therein, and means connecting said tubes in series in an electric circuit.
  2. In an electric sign, a casing, a transverse partition in the casing dividing the latter into front and rear compartments, a "neon" tube in one compartment bent to provide a sign, a "neon" tube in the other compartment, a changeable sign producing 30 stencil device closing the latter compartment visualized by the "neon" tube therein, means connecting said tubes in series in an electric circuit, and means for cutting out one of the tubes from the circuit.
- 35 In testimony whereof I hereunto affix my signature.

LOUIS A. KOCH, JR.
